CHIP RELEASING DEVICE FOR
HAND PLANES

Vincent J. Dillon, Jersey City, N. J.

Application April 3, 1951, Serial No. 219,048

9 Claims. (Cl. 145—15)

1

The present invention relates generally to hand tools and more particularly to those such as wood planes.

With devices such as wood planes, the lower edge of an adjustable cutting blade projects through an aperture in the plane and shavings cut from a piece of wood by the blade pass through the aperture and to the upper part of the plane. The undersurface of the plane guides the plane during usage and it is desirable that this undersurface be uninterrupted except for the relatively small aperture through which the cutting blade projects. Frequently, particularly when making heavy cuts with certain types of wood, shavings or slivers jam tightly in the base aperture between the blade and an opposite wall of the aperture. With the usual plane, these jammed shavings have to be removed either by poking them out or by withdrawing the blade in order to enlarge the aperture for their removal; the blade thereafter requiring resetting to correct position. Both methods of removing the jammed shavings are objectionable as they are time consuming; the latter method of withdrawing the blade is even more objectionable as it requires the additional time for resetting the blade.

Attempts have been made to overcome the above jamming difficulty by providing means for temporarily enlarging the blade aperture so as to release the shavings. These previous devices have not been successful for various reasons. Some of them have been too complicated and impractical for commercial manufacture and sale; others have been too fragile to stand up under the rough usage to which the planes are subjected, and still others have not been adapted for building into standard planes but have required the manufacture of an entirely new type of plane.

The present invention aims to overcome the above and other difficulties by providing a new and improved device for releasing jammed shavings from a plane and further contemplates the provision of such a device which may be incorporated into existing types of planes with minimum changes thereto.

An object of the present invention is to provide a new and improved plane.

Another object of the invention is to provide improved means for releasing jammed shavings from a plane.

Another object of the invention is to provide improved means for releasing jammed shavings which may be readily incorporated in existing

2

types of planes with minimum changes thereto.

A further object of the invention is to provide means for releasing jammed shavings from planes and the like that is of relatively simple and inexpensive construction and operation.

A still further object of the invention is to provide a shaving release device that may be readily and inexpensively manufactured.

Other and further objects of the invention will be obvious upon an understanding of the illustrative embodiments about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification,

wherein:

Fig. 1 is a perspective view showing one type of plane embodying the invention;

Fig. 2 is a fragmentary perspective view showing the plane of Fig. 1 with the shaving release means in open position;

Fig. 3 is a fragmentary top plan view showing the plane of Figs. 1 and 2 with the shaving release means in closed position;

Fig. 4 is a fragmentary sectional view taken along line 4—4 of Fig. 3;

Fig. 5 is a sectional view, partly broken away, taken along line 5—5 of Fig. 4; and

Fig. 6 is a fragmentary sectional view similar to that of Fig. 5, but showing a modified construction thereof.

For purposes of clarity the knob-like handle 7 shown at the front of the plane in Fig. 1 has been omitted from Figs. 2—4.

Referring more particularly to Figs. 1—4 of the drawings, there is shown a plane comprising a base having a bottom portion 2 from which project upwardly extending side portions 4 and 5, guiding handles 6 and 7, cutting blade 8 and a customary blade adjusting mechanism. The lower cutting end 10 of the blade projects through the aperture 11 in the bottom portion 2 of the base. The blade adjusting mechanism may be set to position the cutting edge 10 any desired distance below the undersurface 13 of the base.

In usage the undersurface 13 of the bottom portion 2 is pressed against and moved along the piece of wood being worked and shavings pass up through the opening 11 between the front of the blade 10 and an oppositely dis-

posed surface 14. As previously mentioned, the shavings removed by the cutting blade frequently jam tightly between the blade and the oppositely disposed surface 14 so as to completely choke the opening and interfere with or prevent further cutting. The usual blade aperture or slot has a permanently fixed width sufficient to accommodate normal blade adjustments and to permit passage of shavings up over the blade to the upper part of the plane. Making the slot permanently wider to prevent jamming of shavings is objectionable as it interferes with correct operation of the plane; that is, when the width of the aperture is increased enough to eliminate jamming of shavings the corner of a board or some other edge of the surface being planed may project into the releasing opening and prevent movement of the plane or result in a much greater cut being made than is desired. There are other objections to making the slot wider and those referred to are merely exemplary. With the present invention the opening between the blade 10 and the opposite surface 14 is normally as shown in Fig. 4 but it may be readily enlarged to release jammed shavings; this releasing device will now be described.

As shown more particularly in Figs. 3 and 4 applicant's plane is provided with an aperture that extends from a rear fixed edge 18 to a front fixed edge 19, as well as across the width of the plane between the upwardly extending side portions 4 and 5. This aperture is much wider than the blade slot of an ordinary plane. The large aperture may be partially closed by a member 20 that is rotatably mounted at its opposite ends on pins 22 and 23 which extend through the fixed side portions 4 and 5 into suitable recesses in either the rotatable member 20 or an upwardly extending projection 22. In Fig. 5 the members for rotatably supporting the bottom member 20 are shown threaded into the fixed side portions 4 and 5, with reduced ends projecting inwardly from the side portions. If desired, the mounting may comprise screws 25 and 26, such as shown in Fig. 6, threaded into the rotatable member 20 or its upwardly extending projection 22. The bottom surface of the rotatable member 20 lies substantially flush with the undersurface 13 of the plane when in closed position.

When in use, shavings removed by the cutting edge 10 pass up over the blade in the same manner as with the usual plane. If shavings accumulate or jam into the space between the cutting blade and the oppositely disposed surface 14 the rotatably mounted member 20 which carries the surface 14 may be swung about its supporting pins to some open position such as indicated by the dot-dash lines of Fig. 4. In this relationship shavings may fall out of their own accord. After the shavings are removed, the closure member 20 may be quickly swung back to closed position for use in the normal manner.

To facilitate movement of the member 20 between its closed and open positions it is preferably provided with the upwardly extending operating projection 22 that connects through links 29 and 30 with levers 32 and 33, the levers being secured adjacent ends thereof to brackets 35 and 36, shown bolted or riveted to an upper surface of the plane's base. When the member 20 is in closed position the operating levers 32 and 33 lie substantially along the bottom portion 2 of the base and retain the member 20 closed, through the connecting links 29, 30 and operating projec-

tion 22. To open the member 20 and enlarge the aperture in front of the cutting blade 10, the levers 32, 33 are swung upwardly and this swings the links to the dot-dash line position shown in Fig. 4 and simultaneously tilts the member 20 by applying force to its operating projection 22.

Inwardly extending portions 37 and 38 carried by the levers 32 and 33 may be readily engaged with the fingers to lift the levers and preferably these inwardly extending portions are recessed at their undersides as indicated more particularly in Figs. 1, 2 and 4 so that a person's fingers may be easily inserted thereunder. As indicated in Fig. 1, upward movement of the levers may be limited by the inwardly extending portions 37 and 38 contacting shoulders 40 carried by the handle or knob 1.

The links 29 and 30 which connect the levers 32 and 33 with the operating projection 22 may be separate members rotatably connected at their upper ends with the operating projection 22 or may comprise end portions of a rod which extends entirely through an aperture in the operating projection and has its end portions bent forwardly and thence inwardly so as to project through suitable apertures in the respective levers 32 and 33.

When the closure member 20 is in closed position a beveled edge 42 abuts against a correspondingly beveled edge 43 carried by a fixed base portion 15. When the plane is in use any shavings which pass up over the front of the blade or which tend to jam between it and the oppositely disposed edge 14 tend to rotate the closure member 20 about its supports so as to seat the movable beveled edge 42 firmly against the stationary beveled edge 43. There is no tendency for any cutting or jamming forces to open the member 20 and interfere with correct operation of the plane.

The levers 32 and 33 and links 29, 30 are preferably so proportioned and connected that when the levers are down against the fixed portion 15 at the front of the plane (Fig. 4) the axis of the connection 46 between the levers and links lies below, or at least substantially in line with, the axis of the rotatable connection 34 between the brackets, 35, 36, and the levers 32, 33. In this relationship the closure member 20 is held against opening by force applied thereto. It is necessary to lift the levers 32 and 33 and swing them about their rotatable connections 34 with the brackets before the closure member 20 can be opened. While other means, such as cooperating recesses and projections on the levers and fixed portions of the base, may be employed to hold the parts in closed relationship that described is preferred by reason of its simplicity and inexpensiveness.

It will be seen that the present invention provides new and improved means for releasing shavings or slivers which may become jammed in front of the cutting blade of a plane or the like. It is not necessary to use some auxiliary instrument in order to poke the shavings loose, nor is it necessary to change the blade setting in any manner. An operating lever may be quickly lifted upwardly so as to swing a closure member about its rotatable support and enlarge the opening through which the shavings pass. Shavings readily drop out of their own accord when the device is moved to its open position.

When the shavings are out of the way the operating levers may be easily moved back to closed position to thereby close all portions of the aperture, except for the required slot immediately in front of the cutting blade. When

the actuating levers are in closed relationship down against the stationary portion at the front of the plane, they effectively retain the closure member against accidental opening. Any force applied by jammed shavings or the like immediately in front of the cutting blade do not rotate the closure member to an open position but merely force a beveled surface at the front thereof into even firmer engagement with a complementary surface on the stationary part of the plane.

The present invention is of relatively simple construction and operation and does not require complete redesign of a plane in order to incorporate it with the plane, it may be added to planes of usual construction with a minimum of changes thereto. The rugged simplicity of the present device insures its standing up well under conditions of rough usage and provides for its manufacture at relatively small cost. While the invention has been described largely for use in a wood plane, it will be clear that it is equally useful with and may be readily incorporated into other tools of similar nature.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

I claim:

1. In a device of the class described having a base with an aperture therethrough intermediate fixedly positioned front and rear lower portions of the base, a rotatably mounted member for normally closing a portion of said aperture and rotatable from its closed position and an open position, means projecting generally upwardly from said member, operating means including a link rotatably connected with and extending generally laterally from the projecting means for swinging said projecting means and thereby rotating said member, and means carried by a fixed portion of the base for retaining said link against movement to retain the projecting means and member in closed relationship with respect to said aperture.

2. In a device of the class described, having a base with an aperture therethrough, a member rotatably supported on said base for normally closing a portion of said aperture and movable between its closed position and an open position, means secured to and projecting from said member, a link rotatably connected adjacent one end thereof with said projecting means for moving the projecting means and thereby rotating said member, and operating means connected with said link at a location spaced from said projecting means for moving the link and thereby rotating said member.

3. In a device of the class described having a base with an aperture therethrough, a rotatable member for normally closing a portion of said aperture and movable between its closed position and an open position, means secured to and projecting upwardly from said member, a link rotatably connected adjacent one end thereof with said upwardly projecting means for moving the projecting means and thereby rotating said member, and an operating lever rotatably connected adjacent one end thereof with said device

and connected with said link at a location spaced from said one end of the lever for moving the link and thereby rotating said member.

4. In a device of the class described having a base with an aperture therethrough, a rotatable member for normally closing a portion of said aperture and movable between its closed position and an open position, means secured to and projecting upwardly from said member, a link rotatably connected adjacent one end thereof with said upwardly projecting means for moving the projecting means and thereby rotating said member, and an operating lever rotatably connected adjacent one end thereof with said device and rotatably connected with said link at a location spaced from said one end of the lever for moving the link and thereby rotating said member, the axis of rotation between said lever and said link being disposed below the axis about which the lower end of said lever rotates when the rotatable member is in its closed position.

5. In a device of the class described having a base with an aperture therethrough at a location intermediate front and rear portions of the base, a member rotatably supported on said base for normally closing a portion of said aperture and movable between its closed position and an open position, means secured to and projecting upwardly from said member, a link rotatably connected adjacent one end thereof with said upwardly projecting means and extending over said front portion of the base for moving the projecting means and thereby rotating said member, and operating means carried by said front portion of the base and connected with said link at a location spaced from said projecting means for moving the link and thereby rotating said member.

6. A device as claimed in claim 5, in which said front portion of the base has a rear edge with an upwardly facing inclined surface, and said member has a front edge with a downwardly facing inclined surface for abutting against said first inclined surface when the member is in position closing the aperture.

7. A device as claimed in claim 2, in which a pair of said links and operating means are provided for rotating said member, said links and operating means being spaced from each other and located adjacent opposite side edges of the rotatable member.

8. A device as claimed in claim 3, in which said operating lever carries a laterally extending handle portion for facilitating movement of the lever.

9. A device as claimed in claim 2, in which said upwardly projecting means comprises a flange extending substantially the length of said rotatable member, and in which a pair of said links are provided, one being located adjacent and connected with each opposite end of said flange.
